UNITED STATES PATENT OFFICE.

LEON S. PALETOU, OF ORANGE, NEW JERSEY, ASSIGNOR TO WESTINGHOUSE LAMP COMPANY, A CORPORATION OF PENNSYLVANIA.

DESIGN FOR A DISPENSING-CABINET.

59,862.

Specification for Design.

Patented Nov. 29, 1921.

Application filed March 30, 1921. Serial No. 457,059. Term of patent 7 years.

To all whom it may concern:

Be it known that I, LEON S. PALETOU, a citizen of the United States, residing at Orange, in the county of Essex and State of New Jersey, have invented a new, original, and ornamental Design for a Dispensing-Cabinet, of which the following is a specification, reference being had to the accompanying drawing, forming part thereof.

I claim:

The ornamental design for a dispensing cabinet, as shown.

LEON S. PALETOU.
